US00D816350S

(12) **United States Design Patent** (10) **Patent No.:** **US D816,350 S**
(45) **Date of Patent:** **** May 1, 2018**

(54) **VANITY MIRROR**

(71) Applicant: **simplehuman, LLC**, Torrance, CA
(US)

(72) Inventors: **Frank Yang**, Rancho Palos Verdes, CA
(US); **Tzu-Hao Wei**, Hacienda Heights,
CA (US); **Daniel Ballou**, Long Beach,
CA (US)

(73) Assignee: **simplehuman, LLC**, Torrance, CA
(US)

(**) Term: **15 Years**

(21) Appl. No.: **29/597,617**

(22) Filed: **Mar. 17, 2017**

(51) LOC (11) Cl. **06-07**

(52) U.S. Cl.

USPC **D6/309**; D6/310

(58) **Field of Classification Search**

USPC D6/300-314
CPC ... A47G 1/00; A47G 1/02; A47G 1/06; A47G

& Bear, LLP

(57) **CLAIM**

The ornamental design for a vanity mirror, as shown and
described.

DESCRIPTION

FIG. 1 is a top, front, left-side perspective view of a vanity
mirror embodying our design in a first state;

FIG. 2 is a top, rear, right-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and

FIG. 8 is a bottom plan view thereof.

FIG. 9 is a top, front, left-side perspective view of the vanity
mirror embodying our design in a second state;

FIG. 10 is a top, rear, right-side perspective view thereof;

FIG. 11 is a front elevation view thereof;

FIG. 12 is a rear elevation view thereof;

FIG. 13 is a right-side elevation view thereof;

FIG. 14 is a left-side elevation view thereof;

FIG. 15 is a top plan view thereof; and

FIG. 16 is a bottom plan view thereof.

All features in broken line form no part of the claimed
subject matter.

1 Claim, 14 Drawing Sheets
